UNITED STATES PATENT OFFICE

98,775

DESIGN FOR A GAS PROJECTING APPARATUS

Charles J. Manville, Pontiac, Mich.

Application October 18, 1935, Serial No. 59,113

Term of patent 7 years

To all whom it may concern:

Be it known that I, Charles J. Manville, a citizen of the United States, residing in the city of Pontiac, county of Oakland, and State of Michigan, have invented a new, original, and ornamental Design for a Gas Projecting Apparatus, of which the following is a specification, reference being had to the accompanying drawing, forming part thereof.

In the drawing, Figure 1 is a side elevational view of the gas projecting apparatus showing my new design;

Figure 2 is a front end elevational view of the gas projecting apparatus shown in Figure 1;

Figure 3 is a top plan view of the apparatus illustrated in Figure 1.

My design is characterized by the configuration of the cartridge carrier or magazine and its relation to the breech structure and the grip portions arranged forwardly and rearwardly of the cartridge magazine.

I claim:

The ornamental design for a gas projecting apparatus substantially as shown and described.

In testimony whereof, I affix my signature, this 16th day of October, 1935.

CHARLES J. MANVILLE,
